UNITED STATES PATENT OFFICE.

FRED L. MANNY AND WILLIAM H. KEY, OF BENTON HARBOR, MICHIGAN.

COMPRESSION PUMP.

1,417,677.

Specification of Letters Patent. Patented May 30, 1922.

Application filed March 28, 1921. Serial No. 456,471.

To all whom it may concern:

Be it known that we, FRED L. MANNY and WILLIAM H. KEY, citizens of the United States, residing at Benton Harbor, county of Berrien, State of Michigan, have invented 5 certain new and useful Improvements in Compression Pumps, of which the following is a specification.

This invention relates to improvements in 10 compression pumps, particularly a pump adapted for filling tires.

The objects of the invention are:

First, to provide an improved pump actuating mechanism.

15 Second, to provide an improved compound compression pump.

Objects relating to details and economies of construction will definitely appear from the detailed description to follow.

20 We accomplish the objects of our invention by the devices and means described in the following specification. The invention is clearly defined and pointed out in the claims.

25 A structure which is a preferred embodiment of our invention is fully illustrated in the accompanying drawing, forming a part of this specification, in which:

Fig. I is a side elevation of our improved 30 pump, the handle being broken off.

Fig. II is an enlarged plan view of the same, the hose connection being broken, and the handle being omitted entirely.

Fig. III is a detail sectional elevation on 35 line 3—3 of Fig. II, the handle and hose connection being shown broken and the handle being shown thrown forward.

Fig. IV is a similar detail sectional view with the handle shown drawn back.

40 Fig. V is an enlarged detail sectional view on line 5—5 of Figs. I and II, showing the detail of the rear cross rod connection.

In the drawing, similar numerals refer to 45 similar parts throughout the several views and the sectional views are taken looking in the direction of the little arrows at the ends of the section lines.

Considering the numbered parts of the 50 drawing, the frame 1 is made up of similar symmetrical sides connected together by the cross bars 2 which are adapted to be secured to a suitable base 3 or to the running board of an automobile.

Segment gears 4, 4 are journaled on the ends 55 of the cross rod 5 at 5', 5', the cross rod being shouldered and held in place by screw

nuts 6, 6, washers 7, 7 being interposed to relieve the friction.

The segment gears 4, 4 mesh with segment gears 8, 8 which are journaled on shouldered 60 screws 9, 9 at each side,—see Fig. II.

Pump cylinder 10 is provided with a head 11 bearing trunnions 12 which are journaled in the upper edge or angle of the gear 8,—see Figs. I and II, and provides journaled pivot 65 support therefor.

This pump is provided with a piston head 13 very similar to that of any bicycle pump and has a piston rod 14 journaled at 15' centrally of the cross rod 15 which connects the 70 upper angle of the segment gears 4, 4 together and provides journaled pivot support therefor.

The piston rod 14 is bifurcated at 14', 14' and straddles the centrally disposed handle 75 socket connection 29 which is journaled at the center of the rod 15.

The cylinder 10 has a closed bottom, being preferably formed integral and is connected by a check valve or pump valve 16 to the 80 hose connection 17 which delivers to the second or secondary pump cylinder.

Pump cylinder 18 of much smaller diameter than cylinder 10 is provided with a head 19 having pivots 20 which are secured there- 85 to and connect the lower corners of the segment gears 8. The usual construction of pump piston head 21 is provided for this pump having piston rod 22 which is bifurcated at 22' and journaled upon the cross 90 rod 23 at 23',—see Fig. III. Cylinder 18 is also provided with a bottom head 19' which is provided with a T connection 24 to which the hose 17 from the main cylinder connects.

The lateral connection 25 is provided with 95 a check or pump valve 26 and is connected to the delivery hose 27 which delivers the compressed air to a tire or wherever it may be needed for use.

The handle socket 28 is folded and formed 100 from a sheet of metal having projecting ears 29, 30 which pivotally engage the central portion of the cross rods 15 and 23 for actuating the same, the lever 31 being inserted into this socket and extending to a 105 convenient height for use, the upper portion being broken away.

It will be observed that as these pump cylinders are carried on trunnions supported on the opposed symmetrical gear segments a 110 parallel relation and movement is maintained when the pump handle is recipro-

cated back and forth. This obviates the necessity for any guides for these parts, permits of very simple construction and at the same time secures the most effective action 5 because on the high pressure the segment gears approach the dead center for each cylinder being acted upon, insuring the highest application of power with the minimum effort on the pump handle. The structure 10 could, of course, be used effectively on single cylinders, but especially lends itself to compound pumps as indicated, and we desire to claim the same broadly as a pump actuating means and also specifically in its relation to 15 a compound pump.

Having thus described our invention, what we claim as new and desire to secure by Letters Patent, is:

1. In a compound pump structure, a frame 20 with symmetrical sides, pairs of segment gears pivotally disposed within the said frame and meshing with each other arranged to rock through substantially 90° , pump cylinders disposed between one pair of said 25 gears, the larger of which cylinders is trunnioned at the upper edge of said segment gears and the smaller one of which is trunnioned at the lower edge of said gears, pistons and piston rods with bifurcated ends 30 extending from said cylinders to symmetrically opposed cross rods between the opposed gear segments, a handle centrally disposed between the said second gears and pivotally carried on the said cross rods being retained 35 in position by the bifurcated ends of said piston rods, a connection from the main pump cylinder to the intake end of the secondary cylinder containing a suitable check, and a connection from the secondary pump 40 cylinder containing a check to the delivery hose, coacting for the purpose specified.

2. In a compound pump structure, a

frame, opposed segment gears meshing with each other disposed to rock in said frame, means for actuating the same, a main pump 45 cylinder and an auxiliary pump cylinder trunnioned to one of said gears, with piston and piston rod connections extended and connected by cross rods to the opposed gear in symmetrical relation whereby the rocking 50 of the gears will alternately compress the fluid in said pumps, connections from the main cylinder to deliver to the intake of the auxiliary cylinder, and delivery connection from the auxiliary pump, coacting as 55 specified.

3. In a pump structure, opposed meshing segment gears, a pump cylinder trunnioned to one of said gears with its piston and piston rod pivotally connected symmetrically to 60 the opposed gear, and means for rocking the gears whereby the piston will be forced to the bottom of the pump when the pivotal connections approach the dead center, coacting as specified.

4. Means for operating a pump comprising a frame, pairs of symmetrically opposed intermeshing segment gears journaled to said frame, journal pivot supports on the said opposed gears, one for supporting a cylinder and the other for supporting the piston of a pump in opposed relation whereby the rocking of the gears will cause the said cylinders and pistons to reciprocate in relation to each other, and suitable means for 70 rocking the said gears, as specified.

In witness whereof, we have hereunto set our hands and seals in the presence of two witnesses.

FRED L. MANNY. [L.S.]
WILLIAM H. KEY. [L.S.]
